Des. 62,676

UNITED STATES PATENT OFFICE.

GEORGE I. SCHLEY, OF CHICAGO, ILLINOIS.

DESIGN FOR A LAMP SHADE.

Application filed October 16, 1922. Serial No. 3,990. Term of patent 3½ years.

To all whom it may concern:

Be it known that I, GEORGE I. SCHLEY, a citizen of the United States, residing at Chicago, in the county of Cook and the State of Illinois, have invented a new, original, and ornamental Design for Lamp Shades, of which the following is a specification, reference being had to the accompanying drawings, forming a part hereof.

I claim:

The ornamental design for a lamp shade, as shown.

GEORGE I. SCHLEY.
